UNITED STATES PATENT OFFICE.

WALTER E. EDWARDS, OF BUENA PARK, CALIFORNIA.

RELEASING-PENHOLDER.

1,236,071.

Specification of Letters Patent.

Patented Aug. 7, 1917.

Application filed June 11, 1915. Serial No. 33,555.

To all whom it may concern:

Be it known that I, WALTER E. EDWARDS, a citizen of the United States, residing at Buena Park, in the county of Orange and State of California, have invented certain new and useful Improvements in Releasing-Penholders, of which the following is a specification.

My invention relates to pen holders, and 10 more particularly to an improved pen holder for receiving and clamping a pen, which is simple in construction, cheap to manufacture, strong and durable, and quickly and easily operated.

15 The primary object of my invention is to provide a pen holder of the class above described having a clamping jaw pivotally mounted thereon for engagement with a pen, suitable actuating means being provided 20 for moving the clamping jaw into clamped position.

Another object of my invention is to provide a clamping jaw having reinforcing means associated therewith adjacent the 25 point at which the actuating means engages the same.

A further object of my invention is to 30 provide a pen holder having the improved clamping jaw formed of a single sheet of bendable metal, and an improved releasing 35 means associated therewith.

With the above and other objects in view my invention resides preferably in the construction, combination, and arrangement of 35 parts as hereinafter set forth in the specification and illustrated in the accompanying drawing, in which—

Figure 1 is a longitudinal sectional view of a pen holding shank and handle embodying the improvements of my invention.

Fig. 2 is a similar view showing a pen clamped therein.

Fig. 3 is a transverse sectional view taken on the line 3—3 of Fig. 2.

45 Fig. 4 is a plan view of the blank of bendable metal from which the clamping jaw is formed.

Referring more particularly to the drawings in which the preferred embodiment of 50 my invention is illustrated, I provide a pen holding sleeve 1, which is preferably tubular and internally threaded as at 2 adjacent one extremity. A handle 3 is provided having a threaded shank 4, the free extremity of 55 the threaded shank 4 being frusto-conical

in shape, as indicated at 5, for a purpose which will hereinafter appear.

In Fig. 1 my improved clamping jaw is shown in released position. The clamping jaw preferably comprises a sheet 6 of bendable metal having one extremity thereof enlarged as indicated at 7 to provide a gripping jaw. The gripping portion or jaw 7 is preferably bent into arcuate shape transversely so as to conform to the configuration 65 of the tubular sleeve 1. The sheet 6 is provided, adjacent its opposite extremity, with a plurality of laterally extending ears 8, said ears 8 having openings 9 therein for a purpose which will hereinafter appear. The 70 extremity of the sheet 6 adjacent the ears 8 is bent on the dotted line 10 indicated in Fig. 4 to provide an abutment 11 for a purpose which will hereinafter appear. The ears 8 are bent into the position shown in Fig. 3 75 to provide reinforcing and bearing portions. As shown in Fig. 3, the bearing ears 8 are bent, as at 12, inwardly past the outer marginal edges of the abutments 11 so as to provide strengthening or reinforcing walls 80 performing their function in a manner which will hereinafter appear. The openings 9 are adapted to register and a transverse bolt, rivet, or the like 13 is receivable therethrough, the opposite extremities of the rivet 85 13 being carried by the shank 1, as shown at the points 14 in Fig. 3. The sheet 6 is offset as at 15 substantially intermediate its length and adjacent the inner end of the clamping jaw 7 to provide space between the 90 inner wall of the tubular shank 1 and said sheet to accommodate a flat spring element 16 riveted or otherwise secured, as at 17, to the sheet 6, and bent into yielding engagement as at 18 with the inner wall of the 95 sleeve 1. Attention is called to the fact that the spring 16 need not be riveted to the sheet 6, but may be formed integral therewith by striking a portion of the sheet outwardly to provide a spring, this being within the scope of my invention and possible of use when producing the same for practical use.

A pen is shown clamped in the holder in Fig. 2 and is designated 19, the pen being 105 shown in dotted lines in Fig. 1. When placing a pen in the holder, the handle 3 is slightly unscrewed from the shank 1. By this movement the clamping jaw 7 will be moved to the position shown in Fig. 1 by 110

the action of the spring 16 and a pen may be inserted. By returning the handle 3 to the original position, the contacting portion 5 will engage the abutment 11, causing the 5 jaw to be moved into clamped engagement with the pen. It will be noted that a comparatively small contact surface is presented by the conical end of the handle 3 against the abutment 11 and that the point of contact is offset from the pivot 13. When pressure is exerted on the abutment 11, the reinforcing ears or walls 8 will very effectively perform the function of preventing bending of the abutment when the pen is clamped. 10 Particular attention is called to the fact that when the invention is reduced to practical use, there are only three component parts. These parts are the clamping member, holding shank, and the handle, the clamping 15 member having the pivot ears, spring, and clamping jaw formed integral.

While I have shown and described my invention as possessing a peculiar form and construction it is desired that it be under-

stood that I may make such changes in the 25 details thereof that do not depart from the spirit and scope of the invention as claimed.

Having thus described my invention, what I claim and desire to secure by Letters Patent, is:

A releasing pen holder, including a tubular holding sleeve having an internally threaded extremity, a handle having a threaded end receivable in the threaded extremity, a pen gripping member fulcrumed 35 in the sleeve, said pen gripping member having a resilient gripping jaw and pen guards formed therewith, a reinforced abutment on the gripping member, and a spring for urging the resilient jaw from engagement with the sleeve and the abutment into engagement with the threaded end of the handle.

In testimony whereof I affix my signature in presence of two witnesses.

WALTER E. EDWARDS.
